Primary Examiner — Charles Hanson(74) *Attorney, Agent, or Firm* — James Juo(57) **CLAIM**

The ornamental design for a plug, as shown and described.

DESCRIPTION

FIG. 1 is a perspective view of the plug;
 FIG. 2 is a front elevation view of the plug;
 FIG. 3 is a rear elevation view of the plug;
 FIG. 4 is a right side elevation view of the plug;
 FIG. 5 is a left side elevation view of the plug;
 FIG. 6 is a top plan view of the plug; and,
 FIG. 7 is a bottom plan view of the plug.
 Broken lines appearing in the drawings are intended to be for
 illustrative purposes only and form no part of the claimed
 design.

1 Claim, 4 Drawing Sheets(56)
